LIGHT BULB

Tapio Wirkkala, Helsinki, Finland, assignor to Oy Airam AB, Helsinki, Finland, a Finnish company

Filed Sept. 24, 1968, Ser. No. 13,686

Term of patent 14 years

Int. Cl. D26—01

U.S. Cl. D26—8

FIG. 1.

FIG. 2.

FIG. 1 is a view in elevation of a light bulb in accordance with my invention, the socket therefor being shown in dotted lines; and

FIG. 2 is a top plan view of the light bulb.

The dominant features of my design reside in the portions shown in full lines.

I claim:

The ornamental design for a light bulb, as shown and described.
